MEANS FOR MAKING CIGARETTES

Archie J. Moser, Central City, Iowa

Application August 7, 1939, Serial No. 288,697

6 Claims. (Cl. 131—58)

This invention relates to and means for making cigarettes, and has particular relation to a "vest pocket size" portable device for making the cigarettes.

The "tailor-made" cigarette is relatively expensive compared to the cost of papers and tobacco. A great many smokers would like to roll their own cigarettes in order to effect a saving.

If a person smokes a package of cigarettes a day, his saving, by rolling his own cigarettes, during a year would be approximately \$36.00. However, the rolling of a cigarette by hand is difficult and many persons do not have the patience to learn this process. Cigarette rolling machines have been provided for home use, but these devices are relatively large and are certainly not portable. Furthermore, they can roll only long cut tobacco and thus this materially limits the smoker's field of selection of cigarette tobacco.

It is, therefore, one of the main objects of my invention to provide a small vest pocket size cigarette rolling machine which may be carried about by the smoker.

Another object of my invention is to provide a cigarette making means which will roll cigarettes from any kind of tobacco, long or short cut, dry or moist.

Still another object of my invention is to provide a cigarette rolling means in which the amount of tobacco in the cigarette may be readily regulated and in which the compression of the tobacco may also be regulated.

Other and further features and objects of my invention will be more apparent to those skilled in the art upon a consideration of the accompanying drawing and following specification, wherein is disclosed a single exemplary embodiment of the invention, with the understanding, however, that such changes may be made therein as fall within the scope of the appended claims, without departing from the spirit of the invention.

In said drawing:

Figure 1 is a view in perspective of a device constructed according to one embodiment of my invention.

Figures 2 to 7 inclusive are diagrammatic views in section illustrating the process of rolling a cigarette according to my method and illustrating the functions and operation of the various parts of the rolling means.

Referring now to the drawing, and more particularly to Figures 1 and 2; a device constructed according to a preferred embodiment of my invention is comprised of the approximately semi-

cylindrical shell or base 10 provided with the cupped semi-cylindrical recess 11. The base is preferably provided at opposite ends with the end plates 12 and 13 which project above the base and which are provided with rounded upper edges indicated at 12a and 13a. End plates 12 and 13 may be fastened to the ends of the base by means of the screws 14 and the end plates are provided with curved slots 16 for the purposes hereinafter set forth.

A flexible forming member, such as the spring steel plate 17, is secured to a pin 19, located near the upper edge of or within a recess in one face 17a of the base 10, and fits within the semi-cylindrical recess 11 of the base 10. The free end 17b of the spring plate 17 is preferably rolled around a pin 18 and opposite ends of this pin project through the slots 16 in the end plates 12 and 13. One of the projecting ends of the pin is indicated at 18a in Figure 1.

An angle strip 21 is provided which is likewise pivotally engaged on the pin 19 by means of the small ears 21a. A paper holding angle plate 22 is pivotally engaged to the free edge of the angle strip 21 by means of a pin 23. The ends of the pin 19 are received in openings in the end plates 12 and 13 as indicated in Figure 1.

A cutter plate 24, having an angular flange 24a, is pivotally engaged on the pin 18 by means of rolled ears 24b.

The purpose of the plate 22 generally is to grip the edge of the cigarette paper 26 and to force it downwardly into the cavity 27 formed by the spring steel former plate 17. This operation is indicated in Figures 2 and 3.

In using the cigarette rolling machine, cigarette paper of the correct length and width is laid on top of the flanges 24a of cutter plate 24 and the flange 21a of the plate 21. The paper holding angle 22 is then rotated about the pin 23, as indicated in Figure 3, to grip the edge 26a of the cigarette paper 26 and to force the cigarette paper downwardly into the cavity 27 formed by the former plate 17. The completion of this operation is shown in Figure 3.

The cavity 27a, now formed by the cigarette paper, is filled with tobacco, as indicated at 28. In filling the cavity with tobacco the operator soon learns to utilize the proper amount of tobacco and to distribute it evenly along the length of the cavity. The completion of the filling operation is shown in Figure 4.

The next operation is that of rolling the paper around the tobacco, and this is accomplished by grasping the flange 24 and pushing it forward

so as to carry the free end of the former plate 17 over toward the gripper plate 22, thus wrapping the paper around the tobacco. If too much tobacco is used, a portion of the tobacco will project between the edge 24a of cutter plate 24 and the free edge of the gripper plate 22. If the cutter plate 24 is then firmly pressed toward the plate 22 the edge 24a will act with the edge 22b of plate 22 to cut off this projecting fringe of tobacco. The cut off portion of tobacco is indicated at 28a. The completion of the cutting operation is illustrated in Figure 6.

The next operation is to finish or seal the cigarette. In doing this the plate 24 is pivoted about the pin 18, and at the same time the flange 24a catches under the edge 22b of plate 22 and will rotate the plate 22 upwardly about the pin 23. The plate 24 is then disengaged from the plate 22 and rotated as far as possible to the left about its pivot pin 18 and as illustrated in Figure 7 while the forming plate 17 is, at the same time, held in the position shown to prevent the cigarette from unrolling. The plate 22 is rotated entirely to the right to the position shown in Figure 2. The projecting and exposed end 26a of the cigarette paper may then be moistened and by rotating the sealing edge 21a of the plate 21, as shown in Figure 7, the edge 26a of the paper may be drawn over and sealed to complete the forming of the cigarette. The exposed face of the plate 22 is preferably scored, as at 22b, to assist in cutting off the tobacco. The pin 23 is preferably of spring wire bent slightly to cause the plate 22 to snap to the open and closed positions. It is apparent that I have provided a portable device, small in size, for the rolling of cigarettes. The device is provided with a cutting means to cut away excess tobacco in the event that the operator uses too much tobacco in filling the device. One edge of the cigarette paper is held firmly by the clamping means 22 throughout the rolling operation. The device may be constructed entirely of metal, and all kinds of tobacco, short and long cut, may be used. The amount of tobacco used is easily regulated and the compression of the tobacco in the completed cigarette may be readily regulated. Surplus tobacco may be cut away so that a perfect cigarette may be formed. A method of rolling is employed which will produce perfect cigarettes.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a cigarette rolling machine, a cigarette paper gripping means, a cigarette forming means for forming the tobacco and paper into a cylin-

60 der, and means engageable with the paper gripping means for cutting off the surplus tobacco.

2. In a cigarette rolling machine, a semi-cylindrical base, a spring steel forming means received in the base, a paper gripping means pivotally engaged to one edge of the cigarette forming means, a cutting and pressing means pivotally secured to the other edge of the forming means, and means for guiding the movement of the cigarette pressing, cutting and forming means to cause the forming means to form a cylinder of the tobacco and paper.

3. In a cigarette rolling machine, a base including end members, said end members being provided with guide slots, a forming plate flexible in one direction only, means for pivotally supporting the plate on the base along one longitudinal edge of the plate, means for guiding the other longitudinal edge of the plate in a given path, said means including guide pins engaged in the guide slots, the forming plate normally having a substantially semi-cylindrical shape, and means for positioning and gripping a cigarette paper along the pivotally supported longitudinal edge of the forming plate.

4. In a cigarette rolling machine, a flexible forming plate, means for rolling the plate into a cylindrical form, a positioning and gripping means located along one longitudinal edge of the forming plate, means pivotally attached to the other longitudinal edge of the forming member adapted to cooperate with the paper gripping means to cut off surplus tobacco, and means comprising part of the positioning and gripping means for sealing a cigarette after it is formed.

5. In a cigarette rolling machine, a semi-cylindrical shell, end plates mounted upon the ends of the shell, a flexible forming plate positioned within the shell and normally semi-cylindrical in shape, one edge of the forming plate being pivotally mounted between the end plates, the other longitudinal edge of the forming plate being adapted for movement toward the pivoted edge of the plate, means to guide the movable edge in a given path, means to position and grip a cigarette paper within the forming member, and a cutting member pivotally attached to the movable edge of the forming member and adapted to cooperate with the paper gripping member to cut off surplus tobacco.

6. In a cigarette rolling machine, means adapted to be formed into a cylinder, means for mounting one edge of said means in substantially fixed position, means for guiding the other edge in a given path, means for positioning and gripping a cigarette paper along one edge of the first mentioned means, and means comprising part of the positioning and gripping means for use in sealing a cigarette after it is formed.

ARCHIE J. MOSER.
